PROTECTIVE CAP

Walter E. Dandy, Baltimore, Md.

Application June 18, 1941, Serial No. 398,678

5 Claims. (Cl. 2-3)

This invention relates to head coverings and more particularly to protective head coverings designed to be worn by persons engaged in hazardous occupations.

While the invention, in its broader aspects, is applicable to protective head coverings such as miner's hats or caps and firemen's helmets, it has special utility when applied to baseball caps.

As is well known, baseball players, especially when batting, are frequently struck on the head by a pitched ball and are sometimes badly injured. When at the bat, the side of the player's head is disposed in the direction from which the pitched balls come, and thus the most vulnerable region, namely, the portion of the head just above and forward of the ear, is exposed to the danger of being hit.

The general object of the present invention is to provide a cap having therein a protective shield or guard so positioned as to cover at least the most vulnerable portion of the player's head.

More specifically, the invention contemplates inserting, between the usual fabric body and lining of the cap, a relatively stiff or rigid shield or guard member extending upwardly from the lower edge of the cap.

A further object is to provide a shield or guard member of this character which shall be of double curvature and so shaped that it bears against the head of the wearer only at the margins, thus providing a space or cavity between the shield and the head.

In one form, the invention contemplates the provision of a slide fastener for closing the pocket between the body and lining of the cap, so that the shield or guard member may be placed in or removed from such pocket, as desired.

In another form of the invention, the shield or guard member is permanently secured within the pocket, as by sewing.

The invention further contemplates the provision of a separate shield receiving pocket on each side of the cap, so that the shield may be worn on one or both sides, as desired, or may be shifted from one side to the other in accordance with whether the player is a right or left handed batter.

In order that the invention may be readily understood, reference is had to the accompanying drawing, forming part of this specification, and in which:

Fig. 1 is a side elevation of a baseball cap embodying the invention, the cap being illustrated as in position on the head of a player;

Fig. 2 is a transverse section substantially on the line 2-2 of Fig. 1, looking in the direction of the arrows;

Fig. 3 is a partial transverse section substantially on the line 3-3 of Fig. 1;

Fig. 4 is a side elevation of one of the improved shields or guard members itself; and

Fig. 5 is an edge view thereof.

Referring to the drawing in detail, the cap, which may be of the usual construction, comprises an outer fabric body 1 and a lining 2. Inside the lining, and extending around the lower edge of the cap, is the usual sweat band 3, and the cap may be provided with the customary visor 4.

A pocket is formed at each side of the cap between the fabric body and lining, as by means of a seam or row of stitching 5. In this pocket is enclosed my improved shield or guard member, designated in its entirety by the reference numeral 6.

This shield or guard member is relatively rigid and may be molded from wood pulp, indurated fiber, or plastic material such as some of the synthetic resins, either with or without reinforcing threads or fabric. As shown, it is preferably thicker in its middle portions, tapering to relatively thin edges.

The shield or guard member is of double curvature, that is to say, it is curved both horizontally and vertically, as viewed in Fig. 4, and the degree of curvature is preferably such that the shield bears against the head X of the wearer only at its margins or edges, as indicated at a and b in Fig. 2, so that a space or cavity Y is formed between the body of the shield and the head of the wearer.

The upper edge 6^a of the shield is preferably curved or arcuate, as shown in Figs. 1 and 4, while the lower edge 6^b is substantially straight.

In the form of the invention shown in Figs. 1, 2 and 3, the shield receiving pocket is provided with an opening in the fabric body of the cap, preferably near the lower edge, which opening is closed by means of a suitable slide fastener 7. Thus, this opening affords access to the pocket so that the shield may be inserted in or removed therefrom, as desired. In this way, the shield may be placed in the pocket at either side of the cap, as desired, in order to afford protection to either right or left handed batters.

Instead of providing the pocket with an opening, through which the shield may be inserted or removed, as desired, it may, in some cases, be

preferable to permanently secure the shield within in the cap at the time of manufacture. To this end, the shield may be provided, preferably along its lower edge, with a series of holes 6', through which holes the shield may be sewed directly to the material of the cap. In this modification, a shield may be placed either on one side only of the cap, in which case different caps would be worn by right and left handed batters, or the shield may be placed at both sides of the cap, thus providing an article adapted for the use of either type of batter.

Regardless of the exact construction of the pocket or of whether the shield is removable or permanently secured to the cap, it will be seen that I have provided means for protecting the most vulnerable portion of the side of a player's head from injury by being struck by a ball, the shape of my improved shield or guard member being such as to prevent impact of a ball against a relatively small spot and to distribute the force of the blow over a wide area of the head. This is due to the arcuate shape of the shield providing a space or cavity between itself and the head.

What I claim is:

1. A protective baseball cap comprising a fabric body and a lining, said body and lining forming a pocket between them, said body having an opening affording access to said pocket, means for closing said opening, and a relatively rigid curved shield member insertable into and removable from said pocket through said opening, and of such extent that, when in use, it overlies the side of the head of the wearer just above the ear.

2. A protective cap comprising the usual fabric body and a lining, and a relatively rigid shield member enclosed between said body and lining

and of such extent as to cover that portion of the side of the head of the wearer just above the ear, the lower edge of said shield being substantially straight, and the upper edge curved, and said shield being of arcuate section both vertically and horizontally.

3. A protective cap comprising the usual fabric body and a lining, and having a pocket at each side between said body and lining, and a substantially rigid shield capable of being positioned in either pocket as may be desired, and of such shape and area as to cover the vulnerable region at the side of the head just above the ear of the wearer.

4. A protective baseball cap comprising a cap of conventional type having its lateral area composed of inner and outer fabric layers forming a pocket between them, means for closing said pocket, and a relatively rigid shield of double curvature enclosed within and substantially filling said pocket, said shield being of such extent as to cover the side of the head of the wearer just above the ear.

5. A protective head covering for baseball players comprising a cap of conventional shape having its lateral area composed of inner and outer fabric layers, forming a pocket between them, and a shield of molded plastic material, curved both vertically and horizontally, enclosed and secured within said pocket, said shield having a straight lower edge coinciding substantially with the edge of said cap, and when the cap is in use, extending upwardly toward the top of the head of the wearer, thus overlying the most vulnerable portion of the side of the head just above the ear.

WALTER E. DANDY.
